UNITED STATES PATENT OFFICE.

ALBERT DOERING, OF WATERLOO, WISCONSIN.

BOX CARRIAGE AND RELEASING MEANS.

No. 833,128.

Specification of Letters Patent.

Patented Oct. 9, 1906.

Application filed March 9, 1906. Serial No. 305,081.

To all whom it may concern:

Be it known that I, ALBERT DOERING, residing at Waterloo, in the county of Jefferson and State of Wisconsin, have invented a new and Improved Box Carriage and Releasing Means, of which the following is a specification.

My invention generally relates to improvements in that type of conveyers for transmitting buckets or other material-holders, and particularly to that class of conveyers in which is included a wire-rope tramway; and in its more specific nature it comprehends an improved arrangement of carrier in which the box or holder is pivotally sustained to automatically tilt, detent mechanism mounted on the carrier for engaging the box and holding it to its upright position during its travel to the point of dumping, and means adjustably mounted on the wire cable for automatically tripping the detent, whereby to release the box at the desired points.

My invention also consists in certain details of construction and combination of co-operative parts, all of which will hereinafter be fully explained, pointed out in the appended claims, and illustrated in the accompanying drawings, in which—

Figure 1 is a perspective view of a wire tramway, showing my improved box-carrier and the detent devices therefor mounted thereon and in position of traveling in the direction to the right. Fig. 2 is a similar view showing the carrier at its desired position with the detent in engagement with the tripper device and the box or holder dumped. Fig. 3. is a side elevation of my invention, a portion of the box and one of the supporting-hangers being shown in section to the more clearly illustrate the detent devices hereinafter referred to. Fig. 4 is a detail view of the tripper. Fig. 5 is a similar view of the detent or box locking device. Fig. 6 is a detail cross-section of the hanger-bar b' , showing the safety hook device as engaging with one of the dogs 2. Fig. 7 is a similar view showing the safety device turned to its normal position with its upper finger under the cable 1.

Referring now to the drawings, in which like characters designate like parts in all the figures, 1 designates the cable or wire tramway, and 2 the trip device adjustably mounted thereon, whereby it can be readily moved along the track 1 to clamp the same at any desired point where it is intended the box

shall tilt to discharge the load, and to provide for readily setting the trip 2 I form the same of a spring-metal plate split at one end and bent to form an eye 3 and having its ends arranged to be brought close together or separated by means of a thumb-screw, whereby to bind the rope when the screw is tightened and to ride freely on the rope when the screw is loosened. 65

The trip 2 has a rearwardly-convexed stop whereby to project down below the rope and form a stop 2^a, and the forward end is extended to engage the rope and has a concaved or crotched shape, as at 2^b, to straddle the rope, and thereby hold the stop in a proper alinement and from danger of being flapped laterally when the detent on the carrier engages it, as shown in Fig. 2.

The box-carrier comprises a pair of end 75 uprights b b , a longitudinal cross-bar b' , that is bolted to the upper end of the uprights b b , and a pair of vertically-projected iron straps b^3 , that project up at one side of and above the wire rope 1 and have the upper ends bent 80 over to form the loops for the two carrier-sheaves D D, which engage the wire rope.

Between the lower or pendent ends of the uprights b b is tiltably mounted the box or other holder C, which is pivotally supported 85 by the stud-bolts d on the brackets B, upon which the box tilts, as shown.

The box is so fulcrumed that it normally swings over toward the side, and for holding it vertical to properly receive the load 90 the upper portion of one end c of the box C is provided with a plate which is notched to receive the gravity-drop-catch E, pivotally mounted at e on the short stud e_2 on the back of one of the end uprights, as 95 shown, and this catch is connected to one end of a thin rod the upper end of which passes above the cross-bar of the carrier and has its upper end pivotally connected to a lever f , fulcrumed at f' in a bearing F, mounted on the cross-bar, and has its forward free end extended and formed with a convexed head to engage with the adjustable stop member on the wire rope in such manner that the lever f will be rocked on its fulcrum, the lock, 100 detent, or catch that engages the notched plate raised out of engagement with the box, and the latter left free to tilt sidewise on its end stud-bearings. 105

From the foregoing, taken in connection 110 with the accompanying drawings, it is thought the complete construction and the

advantages of my invention will be readily apparent.

By making the stop member adjustable it can be moved along the rope to any point desired freely, and by reason of its front end, shaped as shown, it will firmly maintain its fixed position, so as the wagon-carriage approaches it will be in proper position to engage with and release the detent on the said carriage.

To provide against the hanger jumping off the cable 1, particularly when rounding curves, I provide safety devices in the nature of a rod H, disposed vertically with respect

- 15 to the hanger-bar b' and journaled in brackets 10 and 20, secured to the bar b', (see Figs. 6 and 7,) by reference to which it will be noticed that the rod H at the upper end has an inwardly-projecting finger h, that extends
- 20 under the cable 1 and prevents the hanger from jumping upward and its sheaves D D leaving the cable, particularly when rounding curves.

The rod H is rotatably mounted in its brackets 10 and 20 and is held to its normal position by a coil-spring i, that connects with a crank member h' on the lower end of the rod H and with the bracket 20, as clearly shown in the drawings, and by reason of 30 such arrangement of parts the finger h when it engages with either of the stops 2 on the cable serves to rock the rod H and turn sidewise to pass over said stop, or by reason of the spring connection i the rod H is automatically returned to its normal position to project its finger h again under the rod after the said finger passes the dog or stop 2.

Having thus described my invention, what I claim, and desire to secure by Letters Patent, is—

1. The combination with the cable, and the stop adjustably mounted thereon, said stop consisting of a spring-metal member having a split loop to engage the cable and a tightening-screw, one end of the stop being 45 bent downward and then upward, the upwardly-bent end being shaped to straddle the cable; of a carrier having traveling sheaves for engaging the cable, a box mounted on the carrier to automatically tilt sidewise, and 50 means for locking the box to its upright position, said means being arranged to engage the stop on the cable and be released thereby, as set forth.

2. The combination with the cable and 55 the stop adjustably mounted thereon, said stop consisting of a spring-metal member having means at one end for frictionally engaging with the cable, said means including a tightening-screw, the forward end of said 60 stop being bent downwardly and then upwardly and the upwardly-bent end shaped to straddle the cable; a carrier having vertical sheaves for engaging the cable, the box mounted on the carrier to automatically tilt 65 sidewise and means for locking the box to its upright position, said means comprising a latch that normally interlocks with the box when the latter is in its upright position, a lever rockably mounted on the upper part 70 of the carrier having a projecting member adapted to engage with the stop on the cable and a link that connects the said lever with the latch, all being arranged substantially as shown and for the purposes described.

ALBERT DOERING.
